ABSTRACT OF THE DISCLOSURE

Carbazole derivatives of the formula:

wherein R₁ and R₂ are the same or different and denote lower alkyl, aminoalkyl, monoalkylated aminoalkyl or dialkylated aminoalkyl or R₁ and R₂ together with N form pyrrolidinyl (1), piperidino, morpholino, piperazinyl (1), 4-(lower alkyl)-piperazinyl (1), 4-(lower hydroxyalkyl)-piperazinyl (1), 4-(acylated lower hydroxyalkyl)-piperazinyl (1); or 4-(alkoxy lower alkyl)-piperazinyl (1) having at most 6 carbon atoms in the alkoxyalkyl radical; and (b) the acid addition salts of (a). These compounds exhibit strong anticonvulsant activity, and the free base and the non-toxic acid addition salts are adapted for use as antiepileptic drugs.

This invention is concerned with new carbazole derivatives of the formula:

and acid addition salts thereof. In Formula I R₁ and R₂ are the same or different and denote lower alkyl, aminoalkyl, monoalkylated aminoalkyl or dialkylated aminoalkyl, or R₁ and R₂ together with N form pyrrolidinyl (1), piperidino, morpholino, piperazinyl (1), 4-(lower alkyl)-piperazinyl (1), 4-(lower hydroxyalkyl)-piperazinyl (1), or 4-(acylated lower hydroxyalkyl)-piperazinyl (1); or 4-(alkoxy lower alkyl)-piperazinyl (1) having at most 6 carbon atoms in the alkoxyalkyl radical. "Lower" alkyl or

2

hydroxyalkyl is intended to indicate, throughout the specification and claims, an alkyl or hydroxyalkyl group having at most 3 carbon atoms.

The Belgian patent specification No. 539,438 discloses carbazole derivatives of the formula:

15 in which A denotes a straight or branched saturated hydrocarbon chain having 2 to 6 carbon atoms, and R₁ represents hydrogen, alkyl having at most 6 carbon atoms, aryl or an arylaliphatic radical, and derivatives thereof
20 which are substituted by halogen, alkyl or alkoxy having at most 6 carbon atoms, aryl or aryloxy in the nuclei and/or methylated in the piperazine ring. These compounds show an anticonvulsant action and are disclosed to be suitable for use as antiepileptics; 1-(4-ethyl-piperazinyl-1)-2-(carbazolyl-9)-ethane being especially effective.

Surprisingly it has now been found that by replacing the saturated group A by the unsaturated 2-butylene group the activity is considerably increased and that this enhanced activity is not confined to 1-(piperazinyl-1)-4-(carbazolyl-9)-2-butenes but can be generally observed in the 1-amino-4-(carbazolyl-9)-2-butenes according to Formula I.

The following Table I shows a comparison of activities 35 between carbazole derivatives according to the invention and 1 - (4-ethyl-piperazinyl-1)-2-(carbazolyl-9)-ethane which is given as the most active of the compounds according to Belgian patent specification No. 539,438. The anticonvulsant action was determined by the electro-shock 40 test [method of Goodman et al., J. pharmacol. 108, 168 (1953)]. ED 50 denotes that dose of known product or of a product according to the invention at which 50% of the test animals are protected against tonic extensor seizure of the hind extremities. Also given in Table I is the 45 oral toxicity on the mouse as LD 50 as well as the oral toxicity on the rat as ED 50 (neurological abnormalities). LD 50 denotes the dose at which 50% of the mice die whereas ED 50 is the dose at which 50% of the rats show first neurological abnormalities (e.g. ataxia).

50 From Table I it is evident that the new carbazole derivatives according to the invention are superior to the preknown 1 - (4-ethyl-piperazinyl-1)-2-(carbazolyl-9)-ethane with regard to the anticonvulsant activity as well as with regard to the ratio of toxicity to activity.

TABLE I

Active substance	Toxicity			
	Electro-shock ED ₅₀ mg./kg., p.o. (rat)	LD ₅₀ mg./kg., p.o. (mouse)	ED ₅₀ mg./kg., p.o. (neurological abnormalities) (rat)	ED ₅₀ mg./kg., p.o. (rat)
(a) Known product: 1-(4-ethyl-piperazinyl-1)-2-(carbazolyl-9)-ethane	32	>450	>400	
(b) Products according to the invention:				
1-diethylamino-4-(carbazolyl-9)-cisbutene(2) oxalate	18	-----	480	
1-piperidino-4-(carbazolyl-9)-cisbutene(2)	15	360	>200	
1-(4-methyl-piperazinyl-1)-4-(carbazolyl-9)-trans-butene(2) dioxalate	16	680	800	
1-(4-methyl-piperazinyl-1)-4-(carbazolyl-9)-cis-butene(2)	17	>460	>200	
1-(4-ethyl-piperazinyl-1)-4-(carbazolyl-9)-trans-butene(2) oxalate	17	-----		
1-(4-β-hydroxyethyl-piperazinyl-1)-4-(carbazolyl-9)-cis-butene(2) dihydrochloride	9	460	325	
1-(4-β-hydroxyethyl-piperazinyl-1)-4-(carbazolyl-9)-cis-butene(2) hydrochloride	13	-----	250	

3

The new compounds of this invention can be administered in dosage unit form to subjects suffering from any type of epilepsy, these pharmaceutical preparations containing, besides the active substance, organic or inorganic solid or liquid carriers suitable for enteral or parenteral administration. The pharmaceutical preparations may be, for instance, in the form of tablets, dragees, or solutions for injection, one dosage unit containing from 15 to 60 mg. of active substance, depending on its nature, on the route of administration and on the physician's prescription, the effective daily dose amounting from 30 to 180 mg. of active substance.

The desired compounds of Formula I are obtained by reducing a compound of the formula:

wherein R₁ and R₂ have the meaning stated above, or an acid addition salt thereof. The reduction is performed, for instance, by treatment with hydrogen in the presence of a catalyst, e.g. Raney iron, Raney nickel or palladium, preferably however, in the presence of a deactivated palladium catalyst; by electrolysis; by treatment with complex hydrides, especially lithium aluminium hydride; or by treatment with metals, such as sodium, potassium or lithium in ammonia. According to the nature of the reducing agent there are usually obtained either cis- or trans-substituted products.

The compounds of Formula II used as starting materials are obtained, for example, by reacting 9-(2-propynyl)-carbazole with amines of the formula HNR₁R₂ in the presence of formaldehyde according to the Mannich reaction.

The desired compounds (I) are also obtained by reacting amines of the formula Z—H, if desired, after prior or during simultaneous action by a condensing agent, with reactive esters of alcohols of the formula

In these formulae, Z and Y are mutually interchangeable and denote on the one hand the carbazolyl(9) group and on the other hand the basic group

As reactive esters of alcohols of the formula

those of hydrohalic acids are especially suitable. The use of a condensing agent is indicated when 9-unsubstituted carbazole is used as starting material. Suitable condensing agents are alkali metals, their hydrides or amides or other alkali metal compounds. Especially suitable is lithium amide.

Hydrohalic acid esters of alcohols of the formula:

which may be used as starting materials are in turn obtainable by reacting carbazole, if desired, after prior or during simultaneous action by a condensing agent of the type mentioned above, with a 1,4-dihalogeno-butene(2).

Compounds obtained according to one of these processes in which —NR₁R₂ forms a 4-unsubstituted piperazinyl(1) group may subsequently be alkylated, hydroxyalkylated or alkoxyalkylated in a way known per se.

4

Furthermore, compounds in which —NR₁R₂ forms a 4-(hydroxyalkyl)-piperazinyl(1) group may subsequently be acylated.

The compounds of Formula I may be obtained and used either as free bases or in the form of their addition salts with suitable acids, e.g. hydrohalic acids, toluene-sulphonic acids, sulphuric, nitric, phosphoric, acetic, oxalic, malonic, succinic, malic, maleic, or tartaric acid.

EXAMPLE 1

5.0 g. of 1-morpholino-4-(carbazolyl-9)-butyne(2) are dissolved in 90 ml. of absolute ethanol, treated with 1.6 g. of a palladium catalyst which has been inactivated with lead salts, and hydrogenated with hydrogen under normal pressure at 20° C. Hydrogenation is stopped when 520 ml. of gaseous hydrogen have been taken up. The reaction mixture is then filtered and concentrated by evaporation in vacuo. The residue is crystallised from ether/hexane, whereby 2.7 g. of 1-morpholino-4-(carbazolyl-9)-cis-butene(2) of melting point 67–70° C. are obtained. The oxalate of this base melts at 185–188° C.

The starting material used in this example is obtained as follows:

10.0 g. of 9-(2-propynyl)-carbazole (melting point 98–25 101° C.) are dissolved in 80 ml. of dioxane, and 2.05 g. of trioxane and 5.1 g. of morpholine are added. After addition of 0.1 g. of copper(II)chloride, the reaction mixture is heated on a steam bath for 1 hour. The reaction mixture is then concentrated by evaporation in vacuo, and 15 the residue is taken up in chloroform/ether and extracted by shaking three times with 2 N hydrochloric acid and once with water. The aqueous solutions are then extracted once with chloroform/ether. The combined aqueous solutions are then made alkaline with ammonia and extracted 20 by shaking three times with chloroform/ether. The chloroform/ether extracts, washed with water and dried with sodium sulphate, yield after concentration by evaporation 13.0 g. of 1-morpholino - 4 - (carbazolyl-9)-butyne(2), which after crystallisation from ether/hexane forms 25 colourless crystals of melting point 95–98° C.

EXAMPLE 2

3.4 g. of 1-dimethylamino-4-(carbazolyl-9)-butyne(2) in 180 ml. of absolute tetrahydrofuran are heated together with 2.0 g. of lithium aluminium hydride under reflux with exclusion of moisture for three days. The excess lithium aluminium hydride is then destroyed by adding ethyl acetate. The residue obtained after evaporation of the solution in vacuo is taken up in ether and separated in a usual manner into neutral and basic constituents, whereby 2.7 g. of crude 1-dimethylamino-4-(carbazolyl-9)-butene(2) are obtained. The oxalate obtained by reacting this base with oxalic acid has after crystallisation from methanol/ether a melting point of 136–137° C.

EXAMPLE 3

5.0 g. of 1-(4-β-hydroxyethyl-piperazinyl-1)-4-(carbazolyl-9)-butyne(2) are dissolved in 100 ml. absolute ethanol, treated with 1.5 g. of a palladium catalyst, which 60 has been inactivated with lead salts, and hydrogenated with hydrogen under normal pressure at 20° C. The hydrogenation ceases when 310 ml. of gaseous hydrogen have been taken up. The reaction mixture is then filtered to remove the catalyst and concentrated by evaporation in vacuo. The residue obtained is crystallised from methanol/ether and yields 3.0 g. of 1-(4-β-hydroxyethyl-piperazinyl-1)-4-(carbazolyl-9)-cis-butene(2) hydrate which after recrystallisation from methanol/ether has a melting point of 116–119° C. The oxalate of the base melts at 70 226–228° C. and the dihydrochloride at 231–234° C.

EXAMPLE 4

5.9 g. of 1-chloro-4-(carbazolyl-9)-trans-butene(2), obtained as mentioned below, in 70 ml. of toluene are heated with 4.0 g. of piperidine at reflux for 22 hours.

After cooling, the reaction mixture is diluted with ether and separated in a usual manner into neutral and basic constituents, whereby 4.3 g. of crude 1-piperidino-4-(carbazolyl-9)-trans-butene(2) are obtained. The oxalate obtained by reacting this base with oxalic acid shows after crystallisation from methanol/ether the form of colourless platelets of melting point 169-172° C.

The 1-chloro-4-(carbazolyl-9)-trans-butene(2) used as starting material is obtained in the following way:

5.0 g. of carbazole in 100 ml. of dioxane are heated for 4 hours at reflux under anhydrous conditions with 0.8 g. of lithium amide. After cooling to about 30° C. 12.5 g. of 1,4-dichloro-trans-butene(2) are added and the reaction mixture is heated for another 12 hours at reflux while stirring. The reaction mixture is then concentrated in vacuo and the residue is taken up in chloroform/ether. The chloroform/ether phase is washed with 2 N hydrochloric acid, 2 N sodium carbonate solution and water and then dried over sodium sulphate and evaporated. There are obtained 9.5 g. of an oily neutral crude product from which 2.9 g. of unreacted carbazole are recovered.

6 EXAMPLE 5

5.2 g. of 1-piperidino-4-(carbazolyl-9)-butyne(2) in 200 ml. of absolute tetrahydrofuran are heated together with 2.7 g. of lithium aluminium hydride at reflux with exclusion of moisture for 2½ days. The excess lithium aluminium hydride is then destroyed by adding ethyl acetate. The residue obtained after evaporation of the solution in vacuo is taken up in ether and separated in a usual manner into neutral and basic constituents. There are obtained 4.0 g. of crude 1-piperidino-4-(carbazolyl-9)-trans-butene(2) which is converted to the oxalate by treating with oxalic acid. After crystallisation from methanol/ether 4.7 g. of 1-piperidino-4-(carbazolyl-9)-trans-butene(2) oxalate in the form of colourless crystals of melting point 168-170° C. are obtained, which product is identical to that obtained according to Example 4.

In a like manner as in the examples previously mentioned there are obtained from the corresponding starting materials the products listed in the following Table II, in which R₁ and R₂ have the meaning stated earlier.

TABLE II

Example		Form	Physical constants
6.....	—N(CH ₃) ₂	Cis..... Base.....	M.P. 77-78° C.
7.....	—N(C ₂ H ₅) ₂	Cis..... Oxalate.....	M.P. 127-129° C.
8.....		Cis..... do.....	M.P. 197-200° C.

12.....	—N(CH ₃)—CH ₂ —CH ₂ —N(C ₂ H ₅) ₂	Cis..... do.....	M.P. 128-130° C.
13.....		Trans..... do.....	M.P. 233-235° C.
14.....		Cis.... Dihydrochloride..	M.P. 234-240° C.
15.....		Cis..... do.....	M.P. 225-229° C.
16.....		Cis..... do.....	M.P. 190-194° C.
17.....		Cis..... do.....	M.P. 210-215° C.
18.....		Cis.... Dioxalate.....	M.P. 222-225° C.
19.....		Cis.... Dihydrochloride..	M.P. 224-227° C.
20.....		Cis.... Base.....	M.P. 74-75° C.
21.....		Cis.... Dihydrochloride..	M.P. 221-225° C.

The oily mother liquor is distilled in a Claisen flask, whereby 0.4 g. of 1,4-dichloro-trans-butene(2) distill over at 17 mm. Hg. The residue from the distillation is taken up in ether and the ethereal solution is filtered through charcoal and then evaporated, whereby 5.9 g. of crude 1-chloro-4-(carbazolyl-9)-trans-butene(2) are obtained.

70 For the manufacture of tablets, the products of this invention can, for instance, be mixed with lactose and granulated with water, paraffin oil, 0.5% sodium alginate or 5% gelatine solution. The dried granulate is compressed into tablets in the presence of the usual auxiliary agents for tabletting, such as talcum, corn starch, colloidal

Production of tablets

silicic acid, or magnesium stearate. In this way, there are obtained, e.g. tablets of the following composition:

	Mg.
1-(4- β -hydroxyethyl-piperazinyl-1-) - 4 - (carbazolyl-9-) - cis-butene(2) dihydrochloride	30
Lactose	65
Colloidal silicic acid	2
Paraffin oil	2
Gelatine	0.5
Magnesium stearate	0.1
Corn starch	5
Talcum	5.4

These 110 mg. tablets, which are provided with a crack-line, can be administered orally in a dosage of half a tablet to one tablet two to six times per day in the treatment of subjects suffering from any type of epilepsy.

We claim:

1. A compound selected from the class consisting of (A): carbazole derivatives of the formula:

wherein R₁ and R₂ are members of the class consisting of lower alkyl, aminoalkyl, monoalkylated aminoalkyl and dialkylated aminoalkyl, or R₁ and R₂ together with N form a member of the class consisting of pyrrolidinyl(1), piperidino, morpholino, piperazinyl(1), 4-(lower alkyl)-

piperazinyl(1), 4 - (lower hydroxyalkyl) - piperazinyl(1), and 4-(alkoxy lower alkyl)-piperazinyl(1); each of the alkyl and alkoxy moieties in any of the above-mentioned substituents containing from 1 to 3 carbon atoms; and (B): acid addition salts of (A).

2. 1-(4- β -hydroxyethyl-piperazinyl-1-) - 4 - (carbazolyl-9-) - cis-butene(2) and its acid addition salts.

3. 1-(4- β -hydroxyethyl-piperazinyl-1-) - 4 - (carbazolyl-9-) - cis-butene(2) dihydrochloride.

4. 1-diethylamino-4-(carbazolyl-9-) - cis-butene(2) and its acid addition salts.

5. 1-piperidino-4-(carbazolyl-9-) - cis-butene(2) and its acid addition salts.

6. 1-(4-methyl-piperazinyl-1-) - 4 - (carbazolyl-9-) - transbutene(2) and its acid addition salts.

7. 1-(4-methyl-piperazinyl-1-) - 4 - (carbazolyl-9-) - cis-butene(2) and its acid addition salts.

8. 1-(4-ethyl-piperazinyl-1-) - 4 - (carbazolyl-9-) - transbutene(2) and its acid addition salts.

9. 1-(4-ethoxyethyl-piperazinyl-1-) - 4 - (carbazolyl-9-) - cis-butene(2) and its acid addition salts.
